HAIRPIN DISPENSER

Norma Bulk, New York, N. Y.

Application April 25, 1949, Serial No. 89,385

6 Claims. (Cl. 312—63)

1

The subject matter of this invention relates to an improvement in hairpin dispensers, and achieves the object of providing means for quick, ready and economical access to hairpins when same are necessary for use in quantities, such as during the dressing of the hair.

In the past it has been necessary, and customary, when dressing hair professionally, to use large quantities of hairpins in order to set the subject's hair, and then remove them from the subject's hair after this purpose has been accomplished. These hairpins are used over and over again innumerable times. Naturally, when they are removed from the hair they are piled up indiscriminately on a tray or similar receptacle, and when the hair dresser desires to use them again on another subject she must fumble in the hairpin receptacle for each separate hairpin, wasting a great deal of valuable time in selecting each hairpin and turning it into proper position for use.

The primary object of this invention is to provide a hairpin cabinet which will present to the user's hand a steady and continuous supply of hairpins maintained in a constant and fixed position for easy accessibility and use, and available one at a time as desired.

Another object of this invention is to eliminate the waste of time and the confusion of the hairdresser who now must fumble in a tray for each individual hairpin and waste additional time in picking it up in proper position for use, thus reducing the time necessary to set the subject's hair with pins, and permitting the hairdresser to be able to take care of more customers in the same time.

A third object of my invention is the provision of a compact cabinet to hold the hairpins in readiness for use at all times.

A further object of my invention is to eliminate the constant loss of hairpins which are left loosely in trays or similar receptacles, as a result of which they fall out, are scattered, etc.

Other salient objects, advantages and functional features will be more readily appreciated from the detailed specification, taken with the accompanying drawings, wherein:

Fig. 1 is a perspective view elevation, partly in cross-section, showing a hairpin dispenser ready for use.

Fig. 2 is a side view, with one wall removed, showing the positioning of the component parts.

Fig. 3 is a top, cross-sectional view, taken on lines 3—3 of Fig. 2.

Fig. 4 is a cross-sectional view, taken on lines 55

2

4—4 of Fig. 2, showing position of hairpins in relation to hairpin slide and roller.

Fig. 5 is an end, cross-sectional view, taken on lines 5—5 of Fig. 2, showing position of magnet 5 in relation to conveyor belt.

Fig. 6 is a side, elevational view showing practical method of refilling cabinet with hairpins.

Similar reference characters designate similar parts throughout the different views.

10 Illustrative of the embodiment shown and disclosed by the drawings, the hairpin dispenser comprises essentially an inclined slide 10 upon which hairpins are placed to slide in series toward a conveyor belt 12 which is connected to rollers 13 and 14. As the hairpins descend in sequence along slide 10 they are drawn up against the conveyor belt 12 by means of magnetic attraction created by a magnet 15 bedded in a container 16 disposed in back of the conveyor belt and in juxtaposition thereto. The magnet 15 is secured in container 16 which is permanently attached to the cabinet 17.

The conveyor belt 12 is trained over rollers 13 and 14 on shafts 18 and 19, which fit into sockets 25 20, 21, 22 and 23 cut into the walls 28 and 29 of the cabinet 17. These shafts rotate freely in the sockets, carrying the endless belt 12, which is composed of a rough, frictional material. This material may be rubber or any suitable material of similar properties.

30 Disposed adjacent to roller 13, and adapted to co-act therewith, is roller 24 mounted on a shaft 25 which is fitted into sockets 26 and 27 in the walls 28 and 29 of the cabinet, and which shaft is adapted to rotate in said sockets. The roller 24 is encased in a sleeve 30, composed of material the same as or similar to the composition of the endless belt 12, and rollers 13 and 24 are positioned in close contact with each other, so that,

40 when hairpin 11 is pulled out of slot 31 from between said rollers, rollers 13 and 24 rotate in opposite directions and belt 12 moves upwardly, bringing with it the next hairpin in line on slide 10 to come between said rollers 13 and 24 and to be held in position between them, by frictional pressure exerted by each roller against the other.

45 Disposed below roller 24 and secured to side wall 29 of the cabinet is a retarding means 32 which serves to narrow the aperture between itself and the endless belt 12 at a point below rollers 13 and 24, to the width necessary to permit a single hairpin to pass through said rollers and into slot 31 at a time. Connected to the shaft 18 and on the exterior side of wall 29 of the cabinet is a stem winding means 33 by means

of which rollers 13 and 24 may be moved in opposite directions to move endless belt 12 upwardly manually, in order to start operation of the dispenser.

In operation, a series of hairpins 11 are placed upon slide 10 at the back of the slide, and the hairpins slide downward in sequence toward the endless belt until the entire line is attracted to the endless belt in sequence. The shape of the slide 10, conforming substantially to the shape of the hairpins, keeps the latter in a uniform line and prevents over-riding. When the first hairpin is drawn to the endless belt 12, by magnetic attraction as shown, the stem winding means is turned counter-clockwise, turning rollers 13 and 24 in opposite directions and moving the endless belt upwardly until the initial hairpin is forced partially out of slot 31 by the co-acting pressures of the rollers. This movement continues until the initial hairpin extends out of the slot 31 in sufficient length so that it can be grasped easily between finger and thumb. As the head of this initial hairpin clears the retarding means 32 the aperture is free to permit the head of the second hairpin in the series to pass the retarding means 32 in an upward direction, as it is drawn along the endless belt by means of the magnetic attraction 15.

As the initial hairpin is drawn completely out through slot 31 manually, the endless belt is drawn upward, bringing with it the second hairpin, which then protrudes from the slot in the identical position of the initial hairpin at rest, as soon as the latter is completely withdrawn through the slot. In continued operation, as each hairpin in turn is drawn out of the cabinet the succeeding hairpin in the series is drawn upward to occupy its predecessor's position, protruding from the slot 31 sufficiently to be manually grasped, until the entire magazine of hairpins is exhausted, all of the parts of the invention being co-ordinated to act interdependently.

The rear of the cabinet 17 is provided with a hinged panel 34, adapted to open outwardly, as shown in Fig. 6, exposing the upper surface of the slide 10 and thus permitting the refilling of the slide with an additional supply of hairpins, as shown. In this manner, hairpins which have been used previously can be re-used again and again. Mounting the hairpins on a charging slide 35 to fill the cabinet may be accomplished in any one of many possible ways. The embodiment shown in Fig. 6 is merely by way of illustration and is not to be construed in any way as a limitation.

Since a certain amount of pull is exerted to draw the hairpin out of the slot 31, sufficient resistance must be provided for the cabinet 17 to remain firmly in place. This resistance may take the form of a heavily weighted base 36 for the cabinet, or means may be provided for securing the base of the cabinet to the surface upon which it rests when in use, in any known manner.

It is manifestly apparent that my invention is superior to and has many distinct advantages over any present means of dispensing hairpins. In use by a professional hairdresser a substantial amount of valuable time is saved by this quick dispensing device. The invention may be used singly or by a series of cabinets sufficient to provide the hairdresser with sufficient hairpins for a day's work. In this way the dispensing cabinets may be refilled with hairpins during idle periods of time, or a lower-salaried employee may be engaged for such purpose.

In addition, the hairpins are conveniently and neatly kept, and loss and destruction of hairpins is kept at a minimum.

While the primary purpose of my invention 5 contemplates its use in beauty parlors and hair dressing salons, nevertheless it will prove of great value and benefit in homes to keep hairpins for personal use, and for any other purpose that it may prove useful.

The embodiment shown in the drawings is by way of illustration, and various changes may be made in the construction and the arrangement of parts without limitation upon or departure from the spirit and scope of the invention, or 15 sacrificing any of the advantages thereof inherent therein, and the drawings are not intended to limit the invention's scope.

I claim:

1. In a device of the described class, a housing 20 for the articles to be dispensed having an extraction slot and a refilling opening, the housing provided with an inclined slide terminating against an endless belt disposed transversely to the slide and carried on rollers mounted on rotating shafts, 25 magnetic means for attracting the articles onto the endless belt, a roller mounted on a rotating shaft disposed parallel to the belt, engaging the belt and co-acting with the belt to frictionally move the articles between them in single fashion 30 toward the extraction slot, retarding means attached to the housing and adapted to release the articles one at a time along the belt toward the extraction slot whereby extraction of an extending article activates the movement in a series of 35 the articles following along the belt toward the extraction slot, and stem winding means attached to the belt shaft to activate initially the movement of the belt and co-acting roller carrying the articles toward the extraction slot.
40. 2. In a device of the described class, a housing for the articles to be dispensed, having an extraction slot and a refilling opening, the housing provided with an inclined slide terminating against an endless belt disposed transversely to the slide and carried on rollers mounted on rotating shafts, 45 a magnet disposed behind the belt to attract the articles onto the belt, a roller mounted on a rotating shaft disposed parallel to the belt, engaging the belt and co-acting with the belt to frictionally move the articles between them in single fashion toward the extraction slot, retarding means attached to the housing and adapted to release the articles one at a time along the belt toward the extraction slot whereby extraction 50 of the extending article activates the movement in a series of the articles following along the belt toward the extraction slot, and stem-winding means attached to the belt shaft to activate initially the movement of the belt and the co-acting roller, carrying the articles toward the extraction slot.
55. 3. In a device of the described class, a housing for the articles to be dispensed, having an extraction slot and a refilling opening, the housing provided with an inclined slide terminating against an endless belt disposed transversely to the slide and carried on rollers mounted on rotating shafts, 60 a magnet disposed behind the belt to attract the articles onto the belt, a roller mounted on a rotating shaft disposed parallel to the belt, engaging the belt and co-acting with the belt to frictionally move the articles between them in single fashion toward the extraction slot, a bar disposed between the slide and the roller, adapted to create 65 a passageway between the bar and the belt to

release the articles one at a time along the belt toward the extraction slot whereby extraction of the extending article activates the movement in a series of the articles following along the belt toward the extraction slot, and stem-winding means attached to the belt shaft and extending outside the container to activate initially the movement of the belt and the co-acting roller, carrying the articles toward the extraction slot.

4. In a device of the described class, a housing for the articles to be dispensed, having an extraction slot and a refilling opening, the housing provided with an inclined slide terminating against an endless belt disposed transversely to the slide and carried on rollers mounted on rotating shafts, a magnet disposed behind the belt to attract the articles onto the belt, a roller mounted on a rotating shaft disposed parallel to the belt, engaging the belt and co-acting with the belt to frictionally move the articles between them in single fashion toward the extraction slot, a bar disposed between the slide and the roller, adapted to create a passageway between the bar and the belt to release the articles one at a time along the belt toward the extraction slot whereby extraction of the extending article activates the movement in a

series of the articles following along the belt toward the extraction slot, and a stem wheel attached to the belt shaft and extending outside the container to activate initially the movement of the belt and the co-acting roller, carrying the articles toward the extraction slot.

5. The device according to claim 4 and provided with a weighted base.

6. The device according to claim 4, wherein the slide is shaped to conform to the contour of the hairpins mounted thereon.
